UNITED STATES PATENT OFFICE.

WILLIAM JOSEPH BISSONNET, OF HOUSTON, TEXAS.

OIL-BURNER.

No. 920,419.

Specification of Letters Patent.

Patented May 4, 1909.

Application filed January 15, 1908. Serial No. 411,008.

To all whom it may concern:

Be it known that I, WILLIAM JOSEPH BISSONNET, a citizen of the United States, residing at 1114 Maury street, Houston, in the 5 county of Harris and State of Texas, have invented certain new and useful Improvements in Oil-Burners, of which the following is a specification.

This invention relates to burners and more 10 particularly to crude petroleum or alcohol burners, and has for an object to provide means for superheating air before discharging the same to the burner proper and thus cause a more perfect combustion to secure a 15 maximum amount of heat.

Other objects and advantages will be apparent from the following description and it will be understood that changes in the specific structure shown and described may be 20 made within the scope of the claims without departing from the spirit of the invention.

In the drawings forming a portion of this specification and in which like characters of reference indicate similar parts in the several views, Figure 1 is a side elevational view of the present burner, Fig. 2 is a vertical longitudinal sectional view through the same, Fig. 3 is a transverse sectional view on the line 3—3 of Fig. 2, Fig. 4 is a transverse 25 sectional view on the line 4—4 of Fig. 2, Fig. 5 is a transverse sectional view on the line 5—5 of Fig. 2, Fig. 6 is a perspective view of the air supply pipe showing its connection with the superheating coil, Fig. 7 is a vertical 30 longitudinal sectional view through a locomotive boiler showing the application of the 35 present burner thereto.

Referring now to the drawings, there is shown a burner comprising a union 11, and 40 a mixing chamber 12, ending in the tip 14, having the centrally disposed discharge opening 15. The chamber 12 is enlarged or outwardly flared at its rear end or base, as shown at 13, and is provided upon its top or 45 upper side with an oil inlet pipe 16, receiving its supply from a suitable source not shown. The rear end of the casing is provided with a plurality of securing ears 17 arranged to register with similar ears 18 formed at the 50 inner end of the union 11.

The union 11 is provided with a lower air inlet passage 19, and above this passage the union 11 is provided with a nozzle 23, comprising the projecting ledge-forming bottom 55 20, the top 22, and the sides 5, 5, projecting beyond the top 22, and being continued and

contacting with the top of the mixing chamber 12, as shown in Fig. 2. This nozzle, as shown in Fig. 4, is of a width less than said mixing chamber 12. The bottom 20 is 60 spaced from the lower wall of this mixing chamber, as shown.

Located above the passage 19 and formed in the union 11, is a steam inlet passage 21, which empties into the nozzle, as shown. 65

The top 22, is somewhat shorter than the bottom 20, and is obliquely positioned relative to the bottom 20. The nozzle 23 is reduced at its forward end as shown in Fig. 2. Held between the projecting sides 5, 5, and 70 curving over the top 22, is the curved plate 25, and this plate is arranged in spaced relation to the upper wall of the mixing chamber 12, as shown. The downwardly curved portion 26 is extended below the top 22 and 75 is slightly spaced at its lower end from the bottom 20 to provide the exhaust slot 24', as shown.

In Fig. 7 of the drawings, there is shown a locomotive boiler A provided with the usual 80 fire box B, and at the forward end the boiler is provided with a smoke box C. The burner is disposed within the fire box of the locomotive with its discharge opening extending inwardly of the fire box, as shown. 85 The air inlet passage 19 is arranged to receive an air pipe 26', and this air supply pipe is extended forwardly beneath the boiler A, and at the front end is connected to a superheating pipe coil 27 located within the smoke 90 box C. The end of the coil is arranged to receive an intake funnel 28, as shown, the air pipe entering the mixing chamber at a point opposite and below said discharge opening. 95

In operation, the oil enters the pipe 16 and 95 is delivered upon the plate 25, from which it drains upon the ledge formed by the bottom 20. In effect, the projecting end of the bottom 20, curved plate 25, and the sides 5, 10 form an oil chamber. Steam under pressure 10 is admitted into the passage 21 and is delivered to the nozzle 23 and is forced out of this chamber through the orifice or slot 24'. As the steam is forced through this orifice, the oil upon the ledge 20 is combined therewith 10 completely atomizing and gasifying it while passing through the nozzle 12. The air enters the funnel 28 and flows through the coil 27 in the smoke box C where it is superheated to a very high temperature, and continues 11 through the pipe 26 and enters the passage 19, and escapes into the nozzle. In

my invention, the air and oil first mix upon the plate 25, before being forced through the nozzle by the escaping steam.

It will of course be understood that denatured alcohol may be used in a burner of the above description with beneficial results.

The nozzle 23, is of a width less than the width of the mixing chamber as shown, so as to provide a heating space below and upon 10 the sides of this portion of the union within the chamber.

Having thus described my said invention, what I claim as new and desire to secure by United States Letters Patent is:—

15 1. In a device of the character described, the combination with a mixing chamber having a discharge opening, of an oil supply pipe entering said chamber from above, an air supply pipe entering said chamber below 20 said oil supply pipe, a nozzle entering said chamber between said air and oil pipes, having a curved drain plate, said oil supply pipe emptying upon said drain plate, said nozzle having its bottom projecting beyond said 25 drain plate, and a steam supply pipe entering said nozzle.

2. The combination with a mixing chamber having a central discharge opening, of an air supply pipe entering said mixing chamber at a point opposite and below said discharge opening, of a nozzle entering said chamber at a point above said air pipe, and being of a width less than said chamber and having a projecting ledge forming bottom, and two upwardly extending sides contacting with 35 the top of said mixing chamber, a curved drain plate held between said projecting sides, and ending proximal to the ledge forming portion of said bottom to provide an exhaust slot, a steam supply connecting with said nozzle, 40 and an oil supply pipe entering said mixing chamber and emptying upon said drain plate, said projecting sides, drain plate and projecting bottom, forming an oil chamber, all arranged as shown. 45

In testimony whereof I affix my signature, in presence of two witnesses.

WILLIAM JOSEPH BISSONNET
